UNITED STATES PATENT OFFICE

104,115

DESIGN FOR A DRESS

Margaret Michelson, New York, N. Y.

Application March 10, 1937, Serial No. 68,094

Term of patent 3½ years

To all whom it may concern:

Be it known that I, Margaret Michelson, a citizen of the United States of America, residing in Manhattan, in the county and State of New York, have invented a new, original, and ornamental Design for a Dress, of which the following is a specification, reference being had to the accompanying drawing, forming part thereof, wherein,

The section seen through the front opening of the dress constitutes an inner panel which is pleated at the hem, as shown.

I claim:

The ornamental design for a dress, substantially as shown and described.

MARGARET MICHELSON.
